UNITED STATES PATENT OFFICE.

AUGUST PAULS, OF BROOKLYN, NEW YORK.

POCKET-SCISSORS.

SPECIFICATION forming part of Letters Patent No. 377,637, dated February 7, 1888.

Application filed October 13, 1887. Serial No. 252,255. (No model.)

To all whom it may concern:

Be it known that I, AUGUST PAULS, a citizen of the German Empire, residing at Brooklyn, in the county of Kings and State of New York, have invented new and useful Improvements in Scissors, of which the following is a specification.

My invention relates to improvements in scissors of that description which can be folded 10 and carried in the pocket.

The object of my invention is to provide scissors the blades of which are held securely in position when folded, and which can be carried in the pocket with safety. This object I 15 accomplish by providing at or near the pivotal point of the scissors a cam having suitable cam-surfaces, one of which is engaged by a spring-arm secured to one of the blades and acts to hold the blades firmly against suitable 20 stops on the bows. The other cam-face is engaged by the spring-arm when the blades are in an operative position, and acts to throw the blades open when the force of the hand on the bows is relaxed, all of which is more fully 25 pointed out in the following specification and claims and illustrated in the accompanying drawings, in which—

Figure 1 represents a face view of my improved scissors when open and ready for use. 30 Fig. 2 is a similar view of the same when folded. Fig. 3 is a face view of a modification.

Similar letters indicate corresponding parts. In the drawings, the letters A and B designate the two blades, which are connected by a 35 pivot, a, and are provided on their ends with bows C and D.

E is a cam, which is located about the pivot a and attached to one of the blades. In the example shown in Figs. 1 and 2 said cam is 40 formed on the end of an extension, d, of the bow D. In Fig. 3 it is formed on the head of the pivot; but it may be directly affixed to one of the blades or formed integral therewith.

The cam is provided with a flat face, e, which 45 is engaged by a spring-arm, F, that is secured to the blade A on the bow side of the pivot a. The action of the spring-arm on the cam tends to normally hold the blades A and B apart, and the latter are thrown open whenever the 50 force of the hand on the bows is relaxed, as

the closing of the blades causes the contact face h of the spring-arm to ride upon a heel of the cam, and the spring-arm is thereby deflected. When the scissors are folded to the position shown in Fig. 2—that is, when the blades are 55 turned backward about their pivot a—the spring-arm F engages a second flat cam-face, f, on the cam E, which face is approximately opposite to the face e. The spring-arm now holds the blades firmly against stops g, g, formed 60 by lateral extensions of the bows C and D. It is evident that one stop g would serve to check the backward movement of the blades; but by preference two stops are used. The points of the blades lie within the bows C and 65 D when the scissors are folded, Fig. 2, and are thereby protected from injury and also prevented from coming into contact with and tearing the material of the pocket. The force of the spring-arm exerted upon the blades 70 when the latter are folded is sufficient to prevent the same from opening inadvertently, and consequently the scissors can be carried in the pocket with safety.

I am aware that it is old to pivot the blades 75 of scissors together in such manner that the blades can be folded back upon the bows and the points protected thereby, and I do not claim such construction, broadly.

What I claim as new, and desire to secure by 80 Letters Patent, is—

1. The combination of the pivoted blades A, B, a cam on one of the blades, and a spring-arm on the second blade in engagement with the cam for holding the blades in their folded 85 position, substantially as shown and described.

2. The combination of the pivoted blades A, B, a cam on one of the blades, stops for arresting the movement of the blades when folded, and a spring-arm on the second blade 90 in engagement with the cam for holding the folded blades against the stops, substantially as shown and described.

3. The combination of the pivoted blades A, B, a cam on one of the blades, located at the 95 pivot-point, and a spring-arm, F, on the second blade, engaging the cam for holding the blades apart when open, substantially as shown and described.

4. The combination of the pivoted blades 100

A B, a cam on one of the blades at the pivot-point, stops on the bows of the blades for arresting the movement of the blades when folded, and a spring-arm, F, engaging the cam when the blades are open for holding the same apart and for holding the folded blades against the stops, substantially as shown and described.

In testimony whereof I have hereunto set my hand and seal in the presence of two subscribing witnesses.
